UNITED STATES PATENT OFFICE.

JACOB RUPERT SCOTT, OF NORTH WEYMOUTH, MASSACHUSETTS, ASSIGNOR OF TWO-TENTHS TO EDWARD H. KAVANAGH AND TWO-TENTHS TO JAMES W. COLGAN, BOTH OF WEYMOUTH, MASSACHUSETTS.

INTERNAL-COMBUSTION ENGINE.

1,230,092.

Specification of Letters Patent. Patented June 12, 1917.

Application filed August 8, 1913. Serial No. 783,775.

To all whom it may concern:

Be it known that I, JACOB RUPERT SCOTT, a citizen of the United States, residing at North Weymouth, county of Norfolk, State of Massachusetts, have invented an Improvement in Internal-Combustion Engines, of which the following description, in connection with the accompanying drawing, is a specification, like characters on the drawing 10 representing like parts.

This invention relates to improvements in internal combustion engines and is especially adapted for use in engines which are supplied with gaseous or liquid fuel. In the latter case the liquid fuel being, of course, vaporized by a suitable carbureter or other vaporizing device. Engines of this character work in cycles, the explosive mixture being drawn in upon the suction stroke of the 15 piston, compressed upon the return stroke, ignited and exploded, causing the piston to be forced to the end of its stroke to supply power to suitable transmission devices, and the burned gas expelled upon the return 20 stroke of the piston. In engines of this character the gas or vaporized fuel is ordinarily mixed with air in a chamber communicating with the cylinder and is drawn into the cylinder directly from such mixing 25 chamber upon the suction stroke of the piston. In starting the engine the crank to which the piston is attached is ordinarily turned over by hand or other power, causing the piston to draw a supply of explosive 30 mixture into the cylinder from the carbureter. When the engine has been standing 35 and becomes cold ordinarily there is not a sufficient amount of explosive mixture drawn into the cylinder upon the first suction stroke 40 to be ignited by the spark producing means within the cylinder and it is necessary to turn over the engine several times before getting a starting explosion.

One of the objects of the present invention is to provide means whereby a sufficient quantity of explosive mixture will be supplied to the cylinder on the first suction stroke to start the engine.

Another object of this invention is to increase the efficiency of internal combustion engines by supplying the explosion chamber thereof with heated and preliminarily expanded charges of explosive mixture.

Frequently in engines of this character the valves between the cylinder and the mixing chamber do not close tightly or with sufficient rapidity and back firing takes place, which injures or destroys the carbureter. Another object of this invention is to overcome this defect by interposing a 55 chamber provided with one or more automatic valves between this mixing chamber and the cylinder.

I have discovered that by providing a normally closed chamber between the main 65 cylinder and the mixing chamber or carbureter and providing valves in the ports communicating with the cylinder and the mixing chamber and means for actuating them at proper intervals the engine will be supplied with sufficient explosive mixture upon 70 the first suction stroke of the piston to start the same, that by heating the explosive mixture in said intermediate chamber a much greater efficiency can be obtained from the 75 engine, and that danger of back firing into the mixing chamber or carbureter can be fully prevented.

This invention may be embodied in various forms of apparatus, certain of which are shown in the accompanying drawings, and described in the following specification. It is to be understood however, that my invention is not limited to the particular forms thus disclosed, but may be incorporated in 85 various other forms of apparatus.

This invention will more fully appear from the accompanying description and drawings and will be particularly pointed out in the following claim.

In the drawings:

Figure 1 represents a plan view of a two cylinder engine embodying my invention.

Fig. 2 is a vertical section on the line 2-2 Fig. 1 showing the intermediate chamber 95 and the relative position of the valves leading to the mixing chamber and cylinders respectively.

Fig. 3 is a vertical section on the line 3-3 Fig. 1 showing the cylinder in section 100 and the relative positions of the inlet and exhaust valves therefor.

In the preferred embodiment of this invention as illustrated in Figs. 1 to 3 inclusive, 1 represents a bed plate from which 105 rise two water jacketed cylinders 2 of the

ordinary form having suitable pistons, not shown. Ports 3 are provided in the sides of the respective cylinders and communicate with valve chambers 4, in which are valves 5, opening in the direction of the flow of the explosive mixture toward the cylinder. The valves 5 are seated in ports 6, which lead to a chamber 7 located intermediate of the cylinder and the carbureter or mixing chamber. A port 8 leads from the intermediate chamber to the conduct 9 which communicates with, and in effect is part of the fuel supply system, which may include the usual carbureter and mixing chamber, not shown. The port 8 is controlled by a valve 10 which likewise is adapted to open in the direction or flow of the explosive mixture. The valves 6 are provided with the stems 11 and are retained normally in their seats by springs 12 which surround said stems and are rendered adjustable by check nuts 13. They are preferably caused to open by suitable mechanism operated through cams or gears from the main shaft of the engine. These valves, however, may be caused to open automatically against the tension of their springs by the suction of the piston.

The valve 10 which leads to the mixing chamber or carbureter is preferably held in its seat by a spring 14 surrounding its valve stem 15 and adjustably secured thereto by check nuts 16. The valve 10 is preferably opened against the tension of its spring 14 by the suction from the cylinder upon the suction stroke of the piston, and is therefore automatic in its action.

In Fig. 3 of the drawings the position of the intermediate chamber 7 and the valve 5 leading therefrom to the cylinder is shown, and upon the opposite side the exhaust port 17 and valve 18 therefor. The valve 18 is provided with a stem 19 which is actuated by a cam or other suitable mechanism driven from the engine shaft to open the valve. It may be closed by similar mechanism, but is preferably closed by a spring 20 surrounding the valve stem and adjustably secured thereto by nuts 21.

Suitable openings 22 may be provided in the upper wall of the intermediate chamber for the introduction and removal of the valves. These openings are screw-threaded and are adapted to be closed by suitable plugs 23 of the usual form.

In the operation of the machine embodying this invention each suction stroke of the piston draws into the cylinder the mixture which is retained in the intermediate chamber and so much additional explosive mixture from the carbureter as is necessary for a complete charge for the cylinder. At the beginning of the compression stroke the valves 5 are released from the cam or other mechanism and are caused to close by their springs 12. The valve 10 like-

wise is forced into its seat by its spring 14, thus trapping so much explosive mixture as has been drawn into the intermediate chamber during the suction stroke of the piston. The mixture thus trapped in the intermediate chamber is retained during the explosion stroke and all of the subsequent strokes prior to the next suction stroke when the chamber is again emptied into the cylinder and the process repeated so long as the engine continues to run.

When the engine is stopped in the usual manner by cutting out the spark in the cylinder, a charge of explosive mixture will be retained in the intermediate chamber and when the engine is again started will be immediately drawn into the cylinder ready to be exploded upon the completion of the compression stroke. This is found to aid very materially in starting the engine and I have experienced no difficulty in starting immediately without turning the engine over more than once, as is ordinarily necessary in starting engines of this character.

The efficiency of the engine is also greatly increased in the use of this invention by heating and expanding the explosive mixture in the intermediate chamber prior to its introduction into the cylinder. In the preferred forms of apparatus embodying my invention the intermediate chamber is placed adjacent to and between the cylinders of the engine, where a plurality of cylinders are used, as illustrated in Figs. 1, 2, and 3, and adjacent to the cylinder where a single cylinder is used. By reason of this position the walls of the intermediate chamber receive a considerable amount of the heat from the walls of the engine cylinder or cylinders. If it is found desirable to supply additional heat to the intermediate chamber the exhaust from the cylinder may be caused to pass through a jacket surrounding or extending along one or more of the walls of the intermediate chamber, as above described.

It will be obvious that in the use of this invention the heated and expanded gaseous mixture is in a much more ready condition for ignition than a non-heated mixture would be and I have found that the efficiency of the engine is very greatly increased thereby.

It is understood that this invention may be embodied in other forms within the meaning and scope of the following claim.

Having fully described my invention what I claim as new and desire to secure by Letters Patent is:

In an internal combustion engine comprising a plurality of cylinders and pistons therefor, fuel supplying means, a heating chamber intermediate said fuel supplying means and said cylinders located at one side of and adjacent to said cylinders and hav-

ing a common wall with said cylinders, inlet ports leading from said heating chamber to said cylinders, valves for said ports, a port leading from said fuel supplying means to said heating chamber, a suction operated valve for said last mentioned port, all of said valves being located upon the same side of the cylinders whereby the explosive mixture will be trapped in said intermediate cham-

ber and heated preparatory to its introduction into the cylinders.

In testimony whereof, I have signed my name to this specification, in the presence of two subscribing witnesses.

JACOB RUPERT SCOTT.
